UNITED STATES PATENT OFFICE.

JOHN V. MEARES, OF MALVERN, NEAR MELBOURNE, VICTORIA, AUSTRALIA.

MEANS FOR CONCRETE CONSTRUCTION.

Application filed November 28, 1921. Serial No. 518,380.

To all whom it may concern:

Be it known that JOHN VINCENT MEARES, a citizen of the Commonwealth of Australia, and resident of 48 Cawkwell Street, Malvern, near Melbourne, in the State of Victoria, Commonwealth of Australia, has invented a certain new and useful Means for Concrete Construction, of which the following is a specification.

10 The invention relates to a simple and strong construction of concrete walls of which each web is made in one integral part.

The invention comprises:—

(a) The making of tapered coreboxes of wood, metal or the like of any desired dimensions, and having the outer faces, if made of other material than metal, or metal sheeting to allow of the easy withdrawal of the coreboxes after a course of wall is completed.

(b) The making of inner and outer forms of similar material to that of the coreboxes, of any desired dimensions, but the use of metal sheeting is discretionary. Very thin pieces of bevelled wood or iron or the like are fixed at intervals to the inner faces of the outer forms throughout their height. These will leave grooves in the outer face of the wall, when the forms are removed, which 30 grooves will allow for the action of changes of temperature of the walls.

(c) The making of tie-holders specially shaped pieces of wood or any suitable material—which are placed between the ends of succeeding coreboxes, at the corners, at the door and window reveals and in the main wall wherever ties are intended to be placed. These hold iron or steel ties in position until the concrete is placed round the ties, and are 40 left there till the concrete is sufficiently set for their removal.

(d) The using of the appliances mentioned under headings (a), (b) and (c) above as follows:—

45 The coreboxes are placed along the foundations between the inner and outer forms, the faces of which will be parallel to each other and the corebox, and at the desired distance from the corebox. The forms are 50 connected to the corebox and to each other by bolts extending through from outside to inside of the combination. The bolts taper so that they may be easily withdrawn when necessary. Devices as shown in Figures 11, 55 12 and 12^a, may be used in lieu of bolts. These devices will be explained in detail at

a later stage. The tie-holders are placed in position between the ends of the coreboxes, and the ties are inserted in the grooves or notches made for the purpose in the abutting 60 faces of the members of the tie-holders.

The concrete is now poured into the space between the inner and outer forms and the coreboxes, and the whole combinations—coreboxes, inner and outer forms, tie-holders, bolts or devices in lieu of bolts—is allowed to remain until it is desired to remove it.

(e) The use of contrivance shown in Figure 14 for the purpose of strengthening the 70 lower portion of a wall of considerable height. This contrivance will be explained later.

The invention will now be described in detail, and for that purpose reference will be 75 made to accompanying diagrams wherein:—

Figure 1 is a plan of the wall embodying the invention.

Figure 2 is a perspective view of the corebox.

Figure 2^a is an end view of a corebox and forms in their relative positions.

Figure 3 is a face elevation of a unit of the inner or outer forms.

Figure 3^a is a plan of a unit of the inner 85 or outer forms.

Figure 3^b is an end elevation of a unit of the inner or outer forms.

Figure 4 is a perspective view of a main wall tie-holder with the members in their 90 relative positions and with a tie held in position.

Figure 5 is a perspective view of a corner tie-holder with the members in their relative 95 positions.

Figure 6 is a perspective view of one member of a main wall tie-holder, or of the major member of a reveal tie-holder.

Figure 6^a is a perspective view of the minor member of a reveal tie-holder.

Figure 7 is a cross sectional view of a wall. Figures 8 and 8^a are views in elevation of a wall.

Figure 9 is a plan of a reveal showing the position of a reveal tie-holder.

Figure 10 is a perspective view of a template.

Figure 11 is an end view of a device for holding the forms in position in the making of a course of the wall.

Figure 11^a is a plan of device shown in Figure 11.

105

110

the wall. Attached to this plate 14 are cleats 14^a. The inner and outer forms 2 and 3 lie between these cleats 14^a and the upper part of the wall last completed and are firmly held in position by the cleats.

When the coreboxes 1 and inner 3 and outer 2 forms are set on the foundations and secured to one another, the concrete is poured into the cavities 9 and 10 between the inner 10 and outer forms 3 and 2 and the coreboxes 1 and when the concrete is set sufficiently the inner and outer forms, tie-holders and coreboxes are removed.

For the remaining course, the same method 15 of erecting appliances and filling cavities is adopted, but to retain the appliances in their new correct position, ties of iron or steel are placed across the cavity, their ends resting on the webs of the course last completed. Slots 1^b in the bottom edges of the coreboxes receive the ties and cause the coreboxes to rest on them.

Figure 14 shows a contrivance for 20 strengthening the lower parts of a wall of considerable height. The members 15 are made of iron or steel of any suitable dimensions, bevelled as shown and are firmly connected by iron or steel rods 15^a of suitable lengths and diameter. The parts 15^c are inserted in holes in members 15 so that the shoulders 15^d rest firmly against the inner faces of the members 15, and the ends of the parts 15^c projecting beyond the outer faces of members 15 are burred so that the rods 15^a may not be withdrawn. These rods 15^a are preferably stepped from each other along the vertically disposed members 15 in zig-zag fashion, or two or more may be in line and the next two or more out of vertical line as illustrated.

What I claim as my invention and desire to secure by Letters Patent is:—

1. In concrete construction, coreboxes placed along foundations between inner and

outer forms the faces of which are parallel 45 to each other and the corebox which is distanced therefrom connecting the forms to the corebox and to each other by fastening devices extending through from the outside to the inside of the said parts, means for 50 maintaining the coreboxes and wall forms in their correct position comprising a template having a mortise bevelled on one side to receive a squared piece of material and a wedge placed on the top edges of the forms 55 and coreboxes so that one of the forms and its stud fits in a recess between shoulders, the corebox fitting in a recess between shoulders, a squared piece of material in the mortise and lying along the vertical face of the 60 other form, and a wedge inserted in the remainder of the mortise.

2. In concrete construction coreboxes provided with tapered studs to which facings are affixed, holes at various points to admit 65 tapering bolts, notches in the bottom edges of the corebox to receive and rest upon ties during the construction of all wall courses except the first one, substantially as described.

3. In concrete construction, corner tie-holders formed in two parts and bevelled and shaped, having abutting faces which meet at such an angle that the horizontal axes of the holders make right angles with each 75 other.

4. In concrete construction, bevel tie-holders each constructed and placed so as to lie between parts of a corebox, another part being set against a jamb lining board as and 80 for the purposes specified.

Signed at Melbourne, Victoria, Australia, this 12th day of August, 1922.

JOHN V. MEARES.

In the presence of—

SIDNEY HENDLEY,
JEANNE C. L. BOUSTIERE.
